UNITED STATES PATENT OFFICE

WILLIAM F. GEIGER, OF JERSEY CITY, NEW JERSEY, ASSIGNOR TO CUNNINGHAM PRODUCTS CORPORATION, OF NEW YORK, N. Y.

DESIGN FOR A POCKET ATOMIZER

Application filed June 11, 1929. Serial No. 31,632. Term of patent 14 years.

To all whom it may concern:

Be it known that I, WILLIAM F. GEIGER, a citizen of the United States, residing at Jersey City, in the county of Hudson and State of New Jersey, have invented a new, original, and ornamental Design for a Pocket Atomizer, of which the following is a specification, reference being had to the accompanying drawing, forming part thereof.

Fig. 1 is a side elevation of a pocket atomizer, showing my new design.

Fig. 2 is a top plan view of the same.

Fig. 3 is a front elevation of the design.

I claim:

The ornamental design for a pocket atomizer, as shown.

WILLIAM F. GEIGER.
